UNITED STATES PATENT OFFICE.

HERBERT E. SHREEVE, OF MILBURN, NEW JERSEY, ASSIGNOR TO WESTERN ELECTRIC COMPANY, OF NEW YORK, N. Y., A CORPORATION OF ILLINOIS.

CURRENT-AMPLIFYING APPARATUS AND CIRCUITS.

1,093,888.

Specification of Letters Patent. Patented Apr. 21, 1914.

Application filed August 20, 1912. Serial No. 715,967.

To all whom it may concern:

Be it known that I, HERBERT E. SHREEVE, subject of the King of Great Britain, residing at Milburn, in the county of Essex and State of New Jersey, have invented a certain new and useful Improvement in Current-Amplifying Apparatus and Circuits, of which the following is a full, clear, concise, and exact description.

10 This invention relates to signaling apparatus for amplifying current impulses and more particularly to repeater apparatus for amplifying wireless signals.

One of the objects of this invention is to provide a repeater for this purpose of few and simple parts easily and rapidly adjustable to meet widely varying conditions. To meet these requirements there is provided a repeater comprising generally a base and a container containing an electromagnetic receiving element having an adjustable pole operated by means carried by the base and a removable microphonic element supported by said container in operative relation to the receiver element and in position to be engaged by a pivotally supported retaining and contact element.

Another object of this invention is to provide apparatus in connection with the repeater and the circuit with which it is connected for determining the most sensitive adjustment of the device, and is attained by the provision of a magneto generator of such design and construction that it may be permanently included in circuit with the repeating element without appreciably affecting the operation of this element.

In the drawings illustrating this invention Figure 1, is a sectional view of a repeater embodying this invention, Fig. 2 is a bottom view of the repeater with parts removed, Fig. 3 is a detail view of the parts of the microphonic element of the repeater, Fig. 4 is a detail view of the receiving and adjusting parts of the repeater, Fig. 5 is a perspective view of the shell or frame of the repeater and Fig. 6 is a diagram of the apparatus and connections of the invention applied to a wireless system showing schematically the apparatus of the testing device.

Referring now to the drawings the frame or shell of the repeater comprises a hollow cylindrical base 5 having formed integrally therewith a container 6 the bore of which is enlarged at the upper end as indicated at 7

to receive the microphone element of the repeater as will hereinafter more fully appear. Secured within the smaller diameter of the container 6 by means of a set screw 8 is a tube 9 of magnetic material. Secured within this tube 9 by means of a set screw 10 is a non-magnetic bobbin 11 having an energizing winding 12 located at one end thereof and being in engagement at its other end with a block 13 of magnetic material secured by means of screws 14, 14 to the tube 9. An adjustable pole 18 of magnetic material having a screw threaded portion 19 engaging a screw threaded opening in the block 13 extends into the bobbin 11 and is provided on its lower end with a squared portion 20. This squared portion 20 engages a corresponding opening 21 in a gear 25 rotatably supported between a bracket 26 and a bottom plate 27 which is secured in a recessed portion 28 of the cylindrical base 5. Meshing with the gear 25 is a pinion 30 secured to a stud 31 which passes through the upper wall of the base 5 and has secured to the upper end thereof a knurled thumb nut 32. Mounted upon the top portion of the base 5 are connecting posts or screws 35, 36, 37, 38 and 39, the post 35 being in electrical connection with the base 5 the others being insulated therefrom. Conductors 40, 40 led through a lined opening in the block 13 and the bobbin 11 are connected with the terminals of the winding 12 and the binding posts 38 and 39. The binding posts 36 and 37 are strapped together by means of a conductor 41.

The microphonic element of the repeater is so constructed that it may be easily removable from the container 6, the purpose being to provide for the insertion of microphonic elements having diaphragms of different natural periods. Referring now to the microphonic element, 50 designates a supporting member having a knurled rim 51 resting upon the upper end of the container 6 and with a cup portion 52 projecting into the enlarged portion 7 of the container 6 and having exterior screw threads. Secured to the lower end of this cup by means of a clamping ring 53 engaging the exterior threads thereof is a metallic electrode or diaphragm 54 preferably formed of magnetic material and gold plated. Secured to this diaphragm 54 is a magnetic stud or plunger 55 which extends into the bobbin 11 into po-

sition to be acted upon by the magnetism caused by the energization of the winding 12. The interior of the cup 52 is provided with an insulating lining 56 which is secured 5 therein by means of a metallic stud 57 having a flat portion engaging said lining 56 and a screw threaded portion extending through a clearance hole 59 in the supporting member 50, and receiving a fastening 10 nut 60 which is insulated from the member 50 by means of an insulating washer 61. Secured to the metallic stud 57 is a hollow 15 conical electrode 65 having an upturned edge 66 and arranged to dip into comminuted material 67 contained by said cup and resting upon the metal diaphragm 54.

The upper end of the metallic stud 57 projects beyond the supporting member 50 into engagement with a spring contact 70 pivotally supported upon the upper end of a post 71, forming a portion of the connecting screw or post 37.

It is quite obvious from the foregoing description that the turning of the knurled 25 thumb nut 32 in a given direction will advance or retract the pole 18 toward or away from the plunger 55 on the diaphragm; and that a microphonic element may be replaced simply by turning the contact spring 70 out 30 of the way, removing the old element and substituting a new one and then moving the contact spring back into engagement with the stud 57 of the new element.

Referring now to the circuit diagram 25 shown in Fig. 6, which illustrates the apparatus and wiring at a receiving station for wireless signals, 75 designates a loose coupled tuning coil having two windings 76 and 77 in inductive relation one terminal of the 40 winding 76 being connected with the antenna the other to ground through a variable condenser 78. The winding 77 has one terminal connected directly with one terminal of an auto-transformer 79, the other terminal 45 of said winding 77 being connected with the other terminal of said auto-transformer through a variable resistance 80 and a condenser 81. A cell 82 is connected in multiple with the variable resistance 80. A 50 detector 83 is connected in parallel with the winding 77 of the loose coupled tuning coil and the auto-transformer 79. The opposite side of the auto-transformer is connected through switch contacts 84 and 85 conductors, 86, 87, 88 and 89 with the binding posts 38 and 39, and thus with the energizing winding 12 of the repeater. A double receiver 90 such as is used for receiving wireless signals is connected by means of switch 60 contacts 91 and 92 and conductors 93 and 94 with the secondary 95 of an induction coil 96. The primary 97 of this induction coil is connected in series with a battery 98 and the microphonic element of the repeater through 65 the binding post 35 and 36. The secondary

95 of the induction coil 96 is preferably made adjustable so that the repeater may be made to work with either a high or a low impedance receiver.

The means provided for testing the repeater for adjustment is as follows: A small magneto generator comprising a permanent magnet 101 and windings 102 and 103 connected with the conductors 88 and 89 leading to the binding posts 38 and 39 of the repeater 70 has located in front of the magnet 101 a steel reed 105 which may be caused to vibrate by striking it with the finger. The vibration of 75 the reed 105 in front of the permanent magnet will induce an alternating current in the windings 102 and 103 which will operate the repeater while the adjusting screw 32 is being turned. The coils of the magneto generator are wound to a high resistance to prevent any appreciable shunting effect on the 80 receiving element of the repeater.

Although intended to be placed in an upright position as shown in the drawing the repeater will operate satisfactorily in any position. The magneto generator is shown 90 as mounted in a box containing the induction coil 96 and although this is a very convenient arrangement provision may be made for mounting it upon the repeater structure or other suitable place.

What I claim is:

1. In a repeater for amplifying current impulses a supporting frame comprising a base and an integrally formed container thereon, a receiving element carried within 100 said container, a microphonic element removably carried by said container in operative relation to said receiving element, and combined contact and retaining means for said microphonic element supported by said 105 base.

2. In a repeater for amplifying current impulses a supporting frame comprising a base and an integrally formed container thereon, a receiving element carried within 110 said container, a microphonic element removably carried by said container in operative relation to said receiving element, a combined contact and retaining device having one end in engagement with said microphonic element, and supporting means for 115 said contact and retaining device secured to said base.

3. In a repeater for amplifying current impulses a supporting frame comprising a 120 base and an integrally formed container, a receiving element carried within said container, a microphonic element removably mounted in the upper end of said container in operative relation to said receiving element, a rotatably mounted contact and retaining means for said microphonic element, and a connecting post secured to said base and supporting said contact and retaining 125 means.

4. In a repeater for amplifying current impulses a frame comprising a base and a container carried thereby said container having an enlarged bore at its upper end, a receiver element located in said container, a unitary microphonic element removably supported in the enlarged portion of said container in operative relation to said receiver element, and a combined contact and retaining device for said microphonic element pivotally supported adjacent to said container. 35
5. In a repeater for amplifying current impulses a frame comprising a base and a container carried thereby, a microphonic element carried by said container, a receiver element located in said container in operative relation to said microphonic element, an adjustable pole for said receiver, and adjusting means for said receiver pole located 40 in said base. 45
- 10 6. In a repeater for amplifying current impulses a frame comprising a base and a container carried thereby, a microphonic element carried by said container, a receiver element located in said container in operative relation to said microphonic element, a rotatably adjustable pole for said receiving element, an adjusting device carried by said base, and operative connections between said 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320
